Primary Examiner — Rashida M Johnson(74) *Attorney, Agent, or Firm* — Bayramoglu Law Offices LLC(57) **CLAIM**

The ornamental design for a chair, as shown and described.

DESCRIPTION

FIG. 1 is a front view of a chair showing our new design;
 FIG. 2 is a rear view thereof;
 FIG. 3 is a left side view thereof, a right side view being a mirror image of the left side view;
 FIG. 4 is a top view thereof;
 FIG. 5 is a bottom view thereof;
 FIG. 6 is a top perspective view thereof; and,
 FIG. 7 is a bottom perspective view thereof.
 The broken lines depict portions of the chair that form no part of the claimed design.

1 Claim, 7 Drawing Sheets(56)
